UNITED STATES PATENT OFFICE.

SAMUEL E. HARSH, OF WABASH, INDIANA.

SHAFT-TUG.

SPECIFICATION forming part of Letters Patent No. 372,973, dated November 8, 1887.

Application filed March 19, 1887. Serial No. 231,577. (No model.)

To all whom it may concern:

Be it known that I, SAMUEL E. HARSH, of Wabash, in the county of Wabash and State of Indiana, have invented certain new and useful 5 Improvements in Shaft-Tugs; and I do hereby declare that the following is a full, clear, and exact description of the invention, which will enable others skilled in the art to which it app pertains to make and use the same, reference 10 being had to the accompanying drawings, and to the letters of reference marked thereon, which form part of this specification.

My invention consists in the combination, with a rigid frame or casting, of a looped strap 15 for securing the shafts against upward movement.

The invention further consists in the combination, with a rigid frame, of a yielding cushion or bearing, upon which the shaft rests, 20 and an independent looped strap for preventing undue upward movement of the shaft.

In the drawings, Figure 1 represents a perspective view of my improved shaft-holder applied to a shaft. Fig. 2 is a side view, 25 partly in section; and Fig. 3 shows in perspective a part of the rigid frame with its yielding seat or bearing-surface.

A represents a frame or casting approximately semicircular in form, and having end 30 loops, a a, and a central depending guard-loop, a'. This frame A is grooved or recessed on both its concave and convex surfaces to receive a band or filling, B, of leather or other soft material. I preferably employ a short 35 strip, which is passed completely around the frame, having its ends overlapped and secured in a suitable manner.

The leather B forms a yielding seat or bearing for the shaft C.

40 D represents a strap secured at one end, d, to one of the ends of the frame. The strap is

then passed upward, and then through the other end loop of the frame and lapped upon itself, the free end d' being provided with a buckle, d'', adapted to engage a strap, E, de pending from the harness saddle. 45

F represents a strap, which passes around the frame A, and is secured to itself below the frame at the point e, to form a loop, F', through which the shaft passes. The depending end f of the strap F is adapted for attachment to the belly-band of the harness. 50

It will be apparent that I thus provide a soft bearing-surface for the shaft, which surface may be readily renewed, and also prevent, by 55 means of the looped strap F, all undue upward play of the shaft within its holder.

Having fully described my invention, what I claim as new, and desire to secure by Letters Patent, is— 60

1. The combination, with a frame or casting provided with end loops, and having a bearing-surface for the shaft of leather or other yielding material, of a looped strap held within the frame to hold the shaft against upward 65 movement in the frame and a strap for securing the frame to the saddle, substantially as described.

2. The combination, with a bearing loop or frame provided with a yielding bearing-surface, of a strap for securing the frame to the saddle of the harness and a looped strap held within the frame for securing the shaft to the belly-band to prevent undue upward play, 70 substantially as described.

In testimony that I claim the foregoing as my own I affix my signature in presence of two witnesses.

SAMUEL E. HARSH.

Witnesses:

ED HARTER,
C. M. HANN.
